UNITED STATES PATENT OFFICE.

HERBERT A. WALLACE, OF NEW YORK, N. Y., ASSIGNOR TO THE UNION SWITCH AND SIGNAL COMPANY, OF SWISSVALE, PENNSYLVANIA, A CORPORATION OF PENNSYLVANIA.

CONTROL OF APPARATUS GOVERNING THE PASSAGE OF CARS OR VEHICLES ALONG A RAILWAY.

No. 830,119.

Specification of Letters Patent.

Patented Sept. 4, 1906.

Application filed June 13, 1906. Serial No. 321,453.

To all whom it may concern:

Be it known that I, HERBERT A. WALLACE, a citizen of the United States, residing in the borough of Manhattan, city, county, and State of New York, have invented certain new and useful Improvements in the Control of Apparatus Governing the Passage of Cars or Vehicles Along a Railway, of which the following is a specification.

10 My invention relates to the control of apparatus governing the passage of cars or vehicles along a railway.

15 My invention more particularly relates to the control of that form of apparatus generally known in the art as "train-stops." This apparatus is preferably automatic in its operation and comprises a trip which has at least two positions, one of which I will herein term its "operative" or "danger" position and the other of which its "inoperative" or "clear" position, a suitable form of motor for moving the trip from its operative to its inoperative position, and suitable means for controlling the supply of motive power to the

20 motor. The trip is preferably moved to its operative position by gravity when power or energy employed to hold it in its inoperative position is cut off from the train-stop, though, if desired, suitable means may be employed for this purpose.

25 In this invention it is intended in the usual operation of the device that when a circuit on a device is closed power will be supplied to move and hold the trip in its inoperative position, and when the same circuit is opened such power will be cut off and the trip will move or be moved to its operative position.

I have not herein illustrated any specific form of train-stop, as my invention relates 40 more particularly to the control of such apparatus, and therefore any form of such apparatus comprising the parts hereinbefore employed may be used. A function of the apparatus is to automatically set the brakes of a car or train or shut off the motor-power from the car or train motors, or both, should a car or train proceed past a "danger-point" without authority. This is generally accomplished by having the trip engage and operate an arm or arms carried by the car or train, which arm operates apparatus provided in the braking or power system of the train or otherwise affects such braking or power sys-

tem. I have not herein illustrated any such arrangement on a car or train, as there are 55 many and they are well understood in the art.

I will now proceed to describe a system of control for such apparatus embodying my invention and will point out the novel features thereof in claims.

In the accompanying drawings, Figure 1 is a diagrammatical view of a portion of a railway, railway-signals located at points along the railway, a train-stop located at two signal-points, and an arrangement of circuits embodying my invention for controlling the operation of a train-stop. Fig. 2 is a view similar to Fig. 1, but illustrating a different condition of some of the circuits and parts 70 due to the presence of a train.

Referring now to the drawings, A A' designate actuating devices for two train-stops, each shown in this case as being a solenoid, although other forms of electrically-controlled or electrically-operated actuating devices may be employed.

B B' designate the trips, each of which is pivoted at b and connected at one end to the core of the adjacent solenoid. The trips of 80 the train-stops are normally or usually in their operative or danger positions and are moved to their inoperative positions and back again to their operative or danger positions by the passage of a car or train along the 85 railway.

C C' designate counterweights, or they may be springs, each connected to its trip to normally bring it to operative or danger position.

H H' designate automatic railway-signals of any approved type. As shown, each railway-signal is provided with a home and distant semaphore; but the latter is not necessary to the operation of my invention. Each 95 railway-signal will preferably be automatically controlled by the passage of a train along the railway, and any of the well-known railway signalling systems employing track-circuits and known as "automatic" systems 100 may be employed. In the drawings I have illustrated one block-section 2 and parts of two other block-sections 1 and 3 at the ends of block-section 2.

E and F are two circuit-controllers operated by the home semaphore of the signal H,

E being closed when the home semaphore indicates "safety" and opened when the home semaphore indicates "danger," and F being closed when the semaphore indicates "danger" and opened when the home semaphore indicates "safety."

E' F' are similar circuit-controllers operated by the home semaphore of railway-signal H'. Each home semaphore will operate 10 two such circuit-controllers.

D is a circuit-controller operated by the movement of the trip mechanism. It is in open position when the trip is in operative position or danger position and closes a circuit only when the trip is in inoperative position or clear position.

D' designates a similar circuit-controller operated by the trip of the train-stop adjacent railway-signal H'. Each trip will operate 20 a similar circuit-controller.

4 and 5 designate line conductors extending along the railway, one being a feeder and the other a return, constituting a part of a circuit which also includes a suitable source 25 of current. (Not shown.)

6 designates a third conductor, which for convenience I will herein designate as a "stop-conductor." One such conductor extends between the circuit-controller F of a home 30 semaphore and the train-stop next in advance.

The operation of my invention is as follows: With no car or train in a block-section or in either of the block-sections adjacent to said 35 block-section the semaphore of the railway-signals will be in the position shown, the trips of the train-stops will be in their operative or danger positions, and all circuits on a train-stop open. Assume now that a car or 40 train (indicated by X) has entered block-section 2 from section 1. The semaphore-blades of the railway-signal H, located at the entrance end of this block-section, will move to "danger," as is usual in automatic signaling 45 systems, thereby operating controller E and closing circuit-controller F. If block-section 3 is also clear of a car or train, the closing of circuit-controller F closes a circuit on the solenoid A', which may be traced as follows: wires 4, 10, circuit-controller F, wires 50 11, 6, 12, 7, circuit-controller E', (see Fig. 1,) wires 8, 13, 14, solenoid A' and wire 9 to return 5. The solenoid A' will then move its trip to its inoperative position, (see Fig. 2,) 55 and in doing so the trip B' will close its circuit-controller D'. As soon as the car or train enters block-section 3 the semaphores of railway-signal H' will move to their danger positions and the controller E' will be 60 opened and F' closed. The opening of circuit-controller E', however, does not set the trip to its operative or danger position, for the closing of circuit-controller D' establishes a circuit from wire 12, through wire 15, 65 circuit-controller D' and wire 16 to the solenoid.

This last-described circuit will be maintained until the car or train X has completely moved out of block-section 2, in which case the home semaphore of railway-signal H will be moved to its safety position, and thereby 70 break the circuit at F, at the same time closing the circuit at E for operating the solenoid A when a car or train enters section 1. It is obvious that unless the home semaphore of railway-signal H' is in its safety position no 75 current can flow through the solenoid A', even should a car or train X enter section 2, and consequently the trip will remain in operative position or danger so long as the home semaphore of railway-signal H' is in danger 80 position. It will be noted that the trip of a train-stop is not moved to its operative or danger position until a car or train has completely moved out of a block-section. It is of course understood that a train or car on 85 section 1 will operate as above described to move the trip B to inoperative position when signal H indicates "safety" and that a car or train on section 3 will under similar conditions move a trip located near the next succeeding section.

I do not wish to be limited to the precise arrangement of train-stop circuits herein described and illustrated, nor limited to the use of a train-circuit embodying my invention 95 with the type of signaling system herein generally stated, as it is obvious that it may be used with different arrangements of signaling systems well known in the art as "overlap," "normal danger," &c. 100

Having described the invention, I claim—

1. In combination with two railway-signals, a train-stop, the trip of which is normally in its operative position, a motor for moving said trip to inoperative position, an 105 open circuit for said motor, and two circuit-controllers in said circuit, one operated to close the circuit only when one of the signals indicates danger and the other operated to close the circuit only when the other signal 110 indicates safety.

2. In combination with two railway-signals, a train-stop, the trip of which is normally in its operative position, a motor for moving said trip to inoperative position, an 115 open circuit for said motor, two circuit-controllers in said circuit operated respectively by the movement of the respective signals, one of said controllers being closed when its signal indicates danger, and the other one 120 being closed when its signal indicates safety, and said motor being inoperative to move the trip until both controllers are closed.

3. In combination with block-sections of a railway, a train-stop for each block-section, 125 the trip of which is normally in operative position, a motor connected to each trip for moving it into inoperative position, railway-signals protecting each section, an open circuit for each motor, two circuit-controllers 130

- in said circuit one being operated to close the circuit when the signal which protects the block in which the stop is located is at danger position, and the other controller being operated to close the circuit when the signal protecting a block in advance is at safety position, and said motor being inoperative until after both controllers are in closed position.
4. In combination with the railway-signals of a block-signaling system, of a train-stop for each block-section, comprising a trip normally in its operative position and an actuating device, a circuit for said actuating device comprising an open circuit-controller closed by the movement of a signal to danger and a closed circuit-controller which is opened by the movement of a signal to danger.
5. In combination with the railway-signals of a block-signaling system, of a train-stop for each block-section comprising a trip normally in its operative position and an actuating device, a circuit for said actuating device comprising an open circuit-controller closed by the movement of a signal, a closed circuit-controller opened by the movement of a signal to danger, and a shunt-circuit which includes a circuit-controller opened and closed by the movement of the trip of the train-stop.
6. The combination with a train-stop comprising a trip normally in its operative position and an actuating device, a circuit for
- 35
said actuating device comprising a normally open circuit-controller and a normally closed circuit-controller, and suitable means for operating the circuit-controllers.
7. The combination with a train-stop comprising a trip normally in its inoperative position and an actuating device, a circuit for said actuating device including an open circuit-controller located at one point and a closed circuit-controller located at a distant point, and a shunt-circuit for said actuating device which includes a circuit-controller operated by the train-stop.
8. In combination with block-sections of a railway, a train-stop for each block-section, the trip of which is normally in operative position, a motor connected to each trip for moving it into inoperative position, railway-signals protecting each block-section, an open circuit for each motor, two circuit-controllers in said circuit, one being operated to close the circuit when the signal which protects the block-section in which the stop is located is at danger position, and the other controller being operated to close the circuit when the signal protecting a block-section in advance is at safety position.

In testimony whereof I have signed my name to this specification in the presence of two subscribed witnesses.

HERBERT A. WALLACE.
